UNITED STATES PATENT OFFICE.

EDWARD COADY, OF OKMULGEE, OKLAHOMA.

TRUNK-BED.

1,159,474.

Specification of Letters Patent.

Patented Nov. 9, 1915.

Application filed February 24, 1915. Serial No. 10,336.

To all whom it may concern:

Be it known that I, EDWARD COADY, a citizen of the United States, residing at Okmulgee, in the county of Okmulgee and State of Oklahoma, have invented new and useful Improvements in Trunk-Beds, of which the following is a specification.

This invention relates to certain novel and useful improvements in trunk beds.

10 In carrying out the present invention it is my purpose to provide a trunk bed wherein the back and top sections will be hingedly connected to each other and the back section likewise connected with the bottom section 15 so that the top and back sections may be swung into the same plane as the bottom section when such sections are in bed formation.

It is also my purpose to provide a bed of 20 the class described wherein the mattress will be composed of end sections corresponding to and disposed upon the end sections of the bed and a center section disposed upon the similar section of the bed and adapted to be 25 folded over onto the end section of the bed formed by the bottom section of the trunk whereby the sections may be folded into trunk formation with ease and facility and the bed clothing placed between the sections 30 of the mattress for transportation purposes.

With the above and other objects in view, the invention consists in the construction, combination and arrangement of parts hereinafter set forth in and falling within 35 the scope of the claims.

In the accompanying drawings: Figure 1 is a perspective view of a trunk bed constructed in accordance with the present invention, the sections being shown as constructed in trunk form; Fig. 2 is a similar view, showing the sections arranged in bed formation; Fig. 3 is a transverse sectional view through the trunk bed with the sections folded in trunk formation; and Fig. 4 is a 45 longitudinal sectional view through the same.

Referring now to the drawings in detail, 1 designates the bottom section of the trunk, 2 the front section having the lower edge 50 suitably secured to the front and rear edge of the bottom section and uprising therefrom, and 3—3 the end sections appropriately fastened to the end edges of the bottom section and uprising therefrom, and

having the forward edges thereof joined to 55 the adjacent end edges of the front section 2.

4 designates the back section of the trunk having the bottom edge thereof pivotally connected to the rear edge of the bottom section 1 of the trunk through the medium of 60 hinges 5, while 6 indicates the top section of the trunk having the rear edge thereof connected with the upper edge of the back section 4 by means of hinges 7.

In the present instance the top edges of 65 the end sections 3 of the trunk are inclined downwardly from the rear ends thereof toward the front section 2 of the trunk and merge into the upper edge of the trunk section 2, while the top section 6 at the ends 70 thereof is provided with depending abutment strips 8 having the lower edges thereof inclined to correspond with the top edges of the end sections 3 and adapted to abut against such end sections when the sections 75 are folded in trunk formation. Depending from the top section 6 at the forward end edge thereof is a strip 9 having the lower edge thereof designed to abut the upper edge of the front section 2. 80

10 designates a mattress comprising end sections 11, 11 disposed upon the sections 1 and 6 respectively and a similar section 12 disposed upon the section 4. Interposed between each section 1, 4 and 6 and the mattress section is a spring section comprising a substantially rectangular frame 13 lying upon the upper surface of the particular section. The sections 13 lying upon the sections 1 and 6, respectively, are appropriately 90 fastened to such sections while the section 13 lying upon the central section 4 is detachably associated with such section. Carried by each frame 13 and projecting upwardly therefrom are coiled springs 14 engaging the 95 under surface of the particular mattress section and designed to yieldingly support the latter. The springs 14 are preferably secured to the respective mattress sections in some suitable manner and the end bars of 100 the frame 13 on the center section 4 are provided with upwardly projecting brackets 15 disposed approximately centrally of the respective bars and pivotally connected with the brackets 15 are links 16 which, in turn, 105 are pivotally connected at 17 with the end sections 3 adjacent to the rear edges thereof. Pivotally connected to the strip 9 and capa-

ble of swinging movement to active and inactive position is a pillow support 18 adapted to be swung to active position when the sections are extended in bed formation and to inactive position when the sections are swung into trunk formation.

In practice the sections 1, 4 and 6 are in trunk formation when it is desired to transport the trunk from place to place, or render the mattress invisible, and in so swinging the sections 4 and 6 the links 16 are swung about their pivots 17 to elevate the frame 13 on the section 4 and invert the mattress section 12, the normal upper surface of the mattress section 12 lying in face to face contact with the similar surface of the end section 11 on the bottom trunk section 1. In this position of the central mattress section 12, the spring carrying frame 13 is uppermost and the section 6 may be swung into trunk formation so that the particular end section 11 of the mattress will lie upon the frame 13 carried by the section 12, the bed clothing being interposed between the sections 11 and 12. When it is desired to move the sections 4 and 6 into bed formation, such sections are swung about their respective pivot points and disposed in the same plane as the bottom section 1. The central mattress section 12 is now disposed upon the section 4 between the end sections 11 and the pillow support 18 swung to active position to receive the pillows, as clearly illustrated in Fig. 2 of the drawings.

The device, when the sections thereof are in trunk formation is provided with suitable securing straps and a lock, as clearly illustrated in Fig. 1, so that the sections may be effectively secured against relative movements.

From the foregoing description, taken in connection with the accompanying drawings, the construction, and mode of operation of my improved trunk bed will be readily apparent. It will be seen that I have provided a bed which may be transported from place to place in the semblance of a trunk, while the sections constituting the trunk may be readily swung into bed formation when desired.

In practice, a supporting frame is preferably fastened to the bed at the corners

thereof to hold a canopy or netting so that the occupant of the bed will be protected when the bed is used out of doors.

I claim:

1. A trunk bed comprising bottom, side and front sections secured to one another, a back section having the lower edge pivoted to the rear edge of said bottom section, whereby said back section may be swung into the same plane as the bottom section, a top section having the rear edge thereof pivotally connected to the top edge of said rear section whereby said top section may be swung into the same plane as the back and bottom sections, a mattress formed of end sections corresponding to said bottom and top sections and disposed thereon respectively, a center section on said back trunk section capable of movement onto the mattress section on the bottom trunk section in the folding of the sections into trunk formation, and spring sections disposed between the respective mattress sections and trunk sections.

2. A trunk bed comprising bottom, side and front sections secured to one another, a back section having the lower edge pivoted to the rear edge of said bottom section, whereby said back section may be swung into the same plane as the bottom section, a top section having the rear edge thereof pivotally connected to the top edge of said rear section whereby said top section may be swung into the same plane as the back and bottom sections and a mattress formed of end sections corresponding to said bottom and top sections and disposed thereon respectively, a center section on said back trunk section capable of movement onto the mattress section on the bottom trunk section in the folding of the sections into trunk formation, and a pillow support pivotally connected to the forward edge of said top section and capable of swinging movement to active and inactive position.

In testimony whereof I affix my signature in presence of two witnesses.

EDWARD COADY.
